UNITED STATES PATENT OFFICE.

HARRY G. ZIMMERMAN, OF PHILADELPHIA, PENNSYLVANIA.

TRAP COVER AND CLAMP.

Application filed June 8, 1927. Serial No. 197,440.

This invention relates primarily to improvements in standard or regulation traps, and the object of the invention is to provide novel means applicable to the traps of all manufacturers for sealing the side opening of the trap without involving the necessity for using the threaded plug commonly employed for that purpose.

Another object of the invention is to provide a device of the character stated above which will not interfere with the usual practice of placing these traps close against a side wall of the building in which the pipe line of which this trap is a part is run.

A still further object of the invention is to provide a closure device of such form that it may be readily altered to fit different sizes of trap.

In the accompanying drawings:

Fig. 1 shows a standard trap equipped with a side closure made in accordance with my invention;

Fig. 2 is a front elevation of the trap shown in Fig. 1;

Fig. 3 is a view in perspective of the closure plate;

Fig. 4 is a view in perspective of the rubber washer forming a part of the device;

Fig. 5 is a view in perspective of the clamping plate or screw;

Fig. 6 is a transverse sectional view illustrating a modification of the device, and

Fig. 7 is a view in perspective of the clamping bar forming a part of the device illustrated in Fig. 6.

With reference to the drawings, 1 indicates a standard or regulation trap equipped with the customary side opening 2 in the lowest part. It is customary to internally thread this side port 2 in order to permit the insertion of a threaded plug which constitutes the usual closure. It is also customary for different manufacturers to form their traps with different sized openings and with different threads requiring the use of their own particular closure plug, and when this plug is lost it is often extremely difficult to replace it. By the present invention, the usual threaded plug is disposed of and a device provided which may be used on any standard trap regardless of the size of the opening 2.

As clearly illustrated, my device comprises a dished closure element 3 having on its concaved side a central boss 4 for reception of

the end of a set screw 5, this set screw being threaded into an opening 6 in a clamping bar 7, and a chain 8 is attached to the ends of the bar 7, as clearly illustrated. One end of the chain 8 is provided with a hook 9 whereby the chain is detachable from an opening 10 at one end of the bar 7, while the opposite end of the chain is permanently fixed in an opening 11 at the opposite end of the bar. In connection with the device, I provide a rubber washer 12.

This device is applied as shown in Fig. 2 by placing the washer 12 over the opening 2 and placing the convexed face of the closure plate 3 against the washer, the plate 70 being held in the port-closing position by means of pressure exerted through the screw 5 in the bar 7, and the bar 7 being anchored to the trap 1 by means of the chain 8 which is passed completely around the trap, 75 as clearly illustrated. Obviously by tightening the screw 5 against the closure plate 3, the latter may be forced with any degree of pressure required against the washer 12, thereby effectively sealing the opening 2. 80 It will be noted that the chain 8 does not extend at the side of the trap 1 appreciably beyond the flange 13 at the top of the trap so that the latter may be placed as close to a wall of a building as when the previous 85 form of closure is used.

In order to accommodate this device to widely differing sizes of trap and opening, I so form the bar 7 that the end sections thereof may be easily broken away from the 90 center section, and at each end of the center section I provide an opening 14 which together function after the same manner as the openings 10 and 11 to hold the opposite ends of the retaining chain 8 when the outer 95 sections of the bar are removed. In the present instance, the bar is weakened adjacent the ends by means of transverse grooves 15 on which the bar may be easily broken to remove the end sections. When 100 smaller traps than that illustrated are used, therefore, these end sections may be broken away and the chain attached in the openings 14, the bar otherwise functioning in the manner described. To accommodate the 105 changes in the size of the opening 2, I also form the closure plate 3 with concentric grooves 16 and 17 on which the outer or peripheral portion may be broken away to provide a plate of the required smaller dimen- 110

sions to correspond with the relatively small clamping bar obtained by removing the end sections, as described above.

In Fig. 6, I have illustrated a modified form of clamp in which the chain 8 and bar 7 are replaced by a substantially L-shaped clamping bar 18. This bar has openings 19 at the straight end thereof for passage of a retaining rod 20, and at its forward or offset end is provided with a threaded opening for the set screw 5. The bar 18 is attached as shown in Fig. 6, with the retaining rod 20 extending across the side of the trap opposite the port 2 in such manner as to prevent the withdrawal of the bar 18, the screw 5 being threaded down against the plate 3 in the manner already described.

There may be still other modifications

without departure from the essential features of the invention.

20

I claim:

A trap comprising a U-shaped section having an opening therein, a convex closing plate adapted to lie over said opening to effectively close the latter, said plate having at least one concentric line of relative weakness on which the plate may be fractured to decrease the diameter, and a clamp for securing the plate in closing position including a trap-embracing member, a bar 25 anchored by said embracing member and having end parts adapted to be broken away to decrease the length thereof, and a screw 30 threaded in the bar and adapted to bear against the said plate.

HARRY G. ZIMMERMAN.
